UNITED STATES PATENT OFFICE.

JABEZ M. SMITH, OF MALVERN, ARKANSAS.

TYPE-WRITER.

1,110,513.

Specification of Letters Patent. Patented Sept. 15, 1914.

Application filed May 6, 1914. Serial No. 836,742.

To all whom it may concern:

Be it known that I, JABEZ M. SMITH, a citizen of the United States, residing at Malvern, in the county of Hot Springs and State of Arkansas, have invented a new and useful Type-Writer, of which the following is a specification.

The present invention relates to improvements in typewriters, one object of the invention, being the provision of pneumatically or fluid pressure actuated means for returning or shifting the carriage and at the same time actuating the line spacing lever to line space the platen.

15 A further object of the present invention, is the provision of a key actuated valve for controlling the supply of pressure fluid to a reciprocating shift actuating engine, whereby the proper return movement 20 against the action of the spring is imparted to the typewriter carriage, thus relieving the operator of the manual labor necessary to return the carriage when moving it for spacing for a new line.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made, within the scope of what is claimed without departing from the spirit of the invention.

35 In the drawings, Figure 1 is a top plan in diagram of a typewriting machine showing the present invention in operable relation thereto, the cylinder of the pressure actuated device being shown in horizontal section. Fig. 2 is a front elevation of the typewriting machine with the present device shown in operable relation thereto, parts being broken away to show the relative position of the fluid actuated means. Fig. 3 is 40 an enlarged detail view showing the key lever and the valve for controlling the cutting off and releasing of the pressure fluid. Fig. 4 is an enlarged detail sectional view through the valve casing.

45 Referring to the drawings, the numeral 1 designates the typewriter frame, which is indicative of any form of typewriting machine, the same being provided with the transversely movable carriage 2, carrying 50 the rotary platen 3. In the present instance, the piston 4 is connected to the car-

riage at one side thereof so that the same will be movable with the carriage, the piston head 5 being connected to the end of the stem for reciprocation within the horizontally disposed cylinder 6. This cylinder 6 is provided with the vent port 7 which is permitted to allow the escape of the pressure fluid from the cylinder 6 when the carriage is at extreme shifted position and ready for a new line, the parts as shown in Fig. 1 being in intermediate position.

A reservoir or tank 8, which is provided with the feeding pipe 9, said pipe 9 either being connected to other air supply or having a pump connection whereby a hand or foot pump may be employed to store air within the tank 8. Leading from the tank 8 is a pipe 10 which extends within the frame of the typewriting machine and has 75 connected therein, the valve 11, a pipe 12 leading from the valve 11 to the cylinder 6 at the opposite end to the port 7, so that the air is permitted to enter the cylinder 6 to move the piston 5 from left to right as 80 viewed in Figs. 1 and 2.

The valve 11 as shown in Fig. 3 is provided with the operating handle 13, which is normally held upwardly so that the valve is held in the position shown in Fig. 4 by 85 means of the spring 14 which is connected to the lever 13 and to the frame 1.

In order to operate the handle 13 and open the valve against the tension of the spring 14, a link 15 is connected to the lever 90 16 intermediate of its pivotal point 18 and the key button 17. Thus it will be seen that as the lever 16 is depressed, the valve 11 is moved to open position and thus permits air to be delivered from the tank 8 into the cylinder to impart movement to the piston 5 from left to right, the piston when seated in the right hand end of the cylinder 6, being beyond the vent 7, so that the air pressure is thus relieved and passes through the 100 vent 7.

In order to provide a means for operating the line shifting lever 19 when the carriage has been actuated by the present fluid operated shifting means, an arm 20 is disposed 105 in the path of the shifting lever 19 and is supported from the frame 1 of the typewriting machine, so as to engage the upturned end of the lever 19 and thus impart the necessary movement thereto to shift the platen 3. 110 Thus at the same time that the carriage and platen is shifted to return position, the line

operating lever is operated to present a new line to be printed upon.

From the foregoing description, it will be evident that the necessary manual labor for shifting or returning the carriage is overcome in the present structure, the desirable cushioning and resilient means being provided due to the compressed air operating upon the piston 5 for returning or shifting the carriage and platen, the same being controlled from the key board so that the operator does not have to move her hands from proper writing position to shift the carriage.

A pressure gage may be connected to the reservoir 8, so that the operator may be kept advised at all times, as to the pressure in the reservoir.

What is claimed is:

In a typewriting machine, the combination of a frame, a carriage mounted thereon for transverse reciprocation, a platen mounted in the carriage for rotation, said platen being provided with a shaft extension upon one end thereof, said shaft extension consti-

tuting a piston rod, a piston connected to the free end of said rod, a pneumatic cylinder surrounding the piston and disposed coaxially with the platen, a bracket connected to the free end of the cylinder and to the frame for supporting the cylinder, said cylinder being provided with an intake port through its lower end and with an air relief port at its opposite end, an air supplying pipe connected to the air supplying port, an air reservoir connected to said pipe, a spring closed valve connected in said pipe, and a key actuated lever operable from the key board of the typewriter and connected to the valve for operating the same in opposition to the spring.

In testimony that I claim the foregoing as my own, I have hereto affixed my signature in the presence of two witnesses.

JABEZ M. SMITH.
